UNITED STATES PATENT OFFICE

2,340,844

HEATING APPARATUS

**Earnest J. Dillman, Detroit, Mich., assignor to
Detroit Lubricator Company, Detroit, Mich., a
corporation of Michigan**

Application March 27, 1943, Serial No. 480,816

5 Claims. (Cl. 237—8)

This invention relates to new and useful improvements in heating apparatus and more particularly to the operation of a hot water boiler, having a circulator for supplying boiler water to a radiator or the like.

An object of the invention is to provide means to render the operation of the circulator ineffective to supply boiler water at temperatures of the boiler water below a desired supply temperature.

Another object as to provide for the control of such a means in accordance with the demand for domestic hot water from a heat exchanger heated by the boiler.

Another object is to directly influence the operation of such a means upon the supply of domestic hot water by the heat exchanger.

The foregoing and other objects will be apparent from the following specification.

The invention consists in the cooperative relation of parts to be more fully described herein-after and the novelty of which will be particularly pointed out and distinctly claimed.

In the accompanying drawing, to be taken as a part of this specification, there is fully and clearly illustrated a preferred embodiment of the invention in which drawing:

Figure 1 is a view of a heating apparatus partially diagrammatic and having certain parts broken away to more clearly show the invention;

Fig. 2 is an enlarged detail view in section of a thermostatic control valve forming part of the invention.

Fig. 3 is a detail view in perspective showing the heat exchange relation of certain conduit members, and

Fig. 4 is a detail view in section showing a modification of a part of the control valve.

Referring to the drawing by characters of reference, 1 designates generally a hot water boiler having a hot water supply line or pipe 2 for supplying the heated boiler water to the usual house heating radiator, for example. The return line 3 from the radiator connects into the boiler 1 in the usual manner, as at 4, and is provided with a pump or hot water circulator 5 driven by an electric motor 6. A room thermostat 7 responsive to the temperature of the air in the space heated by the radiator controls the electric circuit through lead wires 8, 9 of the motor 6. The boiler 1 is heated by an oil burner or the like 10 having its operating circuit 11, 12 controlled by a thermostatic switch 13 responsive to the temperature of the water in the boiler 1.

Positioned in the return line 3 on the inlet side of the circulator 5, there is a thermostatic valve 14 having a casing or housing 15 with an inlet 16 and an outlet 17. Within the casing 15 and controlling flow from the inlet 16 to the outlet 17 and to the circulator 5, there is a valve member 18 of the butterfly type pivotally supported at 19 and operated by a thrust member 20. The casing 15 has an extension 21 providing a chamber 22 in which a temperature responsive operating element 23 is positioned. A bracket 24 carried by the casing 15 supports a housing 25 which carries the element 23, which is preferably a device such as is disclosed in the patent to Vernet, 2,265,586, December 9, 1941. Within the housing 25 there is a spring 26 acting on the thrust member 20 and urging the valve member 18 toward a closed position. The chamber 22 has an inlet 27. Surrounding the supporting member 25 there is a baffle member 28 having ports 28^a and 28^b and operable to restrict and direct flow from the inlet 27 into intimate heat exchange relation with the element 23. Connected to the inlet 27 there is a by-pass pipe 28, see Fig. 1, which connects into the water space of the boiler 1, as at 29, at a point closely adjacent to the coils of a domestic water supply heat exchanger 30 and preferably at a point directly beneath the exchanger, so as to receive the boiler water which has been cooled by down flow convection circulation over the coils of the heat exchanger 30. The pipe 28 adjacent its outlet from the boiler is extended into intimate heat exchange relation, as at 31, with the cold water inlet line or pipe 32, which feeds the exchanger 30. This exchange relation is preferably provided by clamping the pipe 28 to the inlet line 32 by a clamp 33, see Fig. 3. The exchanger 30 has a hot water outlet line 34 leading to the usual points of consumption of the domestic hot water supply. The pipe 28 and chamber 22 provide a by-pass conduit for the boiler water to convey the same into intimate heat exchange relation with the temperature responsive element 23. In Fig. 4, the outlet from the chamber 22 to the outlet 17 and the circulator is through a port 35 in the side wall of the chamber 22. In this form of device, the baffle plate 36 is imperforate and substantially fits the opening of the chamber 22 into the casing 15 so that flow from the inlet 17 to the chamber 22 is directed over the temperature responsive element 23.

The operation of the apparatus is as follows. The boiler thermostat 13 is set to maintain the boiler water temperature at say 170° F., so that whenever the room thermostat 7 calls for heat

and closes the circuit of the circulator motor 6, water, which should be at the desired radiator heating temperature, will be supplied through the conduit 2 to the radiator, the water being withdrawn through the return line 3 to the boiler, assuming that the valve 18 is open. If the water drawn by the circulator 5 through the by-pass pipe 28 is below the desired domestic water heating temperature, say 150° F., for which the thermostatic valve 14 is set, then the temperature of the water drawn by the circulator over the element 23 will be below the temperature at which valve 18 will be opened and accordingly spring 26 will be holding the valve 18 in closed position, with the result that the circulator 5 will not supply water to the radiator and heating of the boiler water will continue without lowering of its temperature by supply to the radiators. When the temperature of the water drawn through the bypass pipe 28 by the circulator reaches the desired minimum temperature of 150° F. for heating the domestic water in the exchanger 30, then the operating element 23 will act through the thrust member 20 against the force of spring 26 and move the valve 18 to open position, so that circulation of water to the radiator will occur. If while the circulator 5 is in operation domestic hot water is drawn from the exchanger 30 through pipe 34, so that cold water is supplied to the exchanger through the inlet pipe 32, then the boiler water adjacent the exchanger 30 will be cooled and the temperature of the water supplied to the pipe 28 from the boiler will decrease. If the temperature of the water supplied by pipe 28 to the element 23 falls below the temperature at which element 23 holds the valve 18 in open position, then the spring 26 will move the valve 18 to closed position so that the boiler water will be utilized exclusively to heat the exchanger 30 to provide hot water for the domestic supply. By extending the pipe 28 in intimate heat exchange with the cold water inlet pipe 32, the operating element 23 will respond more quickly to the withdrawal of domestic water from the exchanger 30 and more quickly close the valve 18. As soon as the withdrawal of water from the exchanger 30 is stopped, the temperature of the water supplied to the pipe 28 will increase, and when it reaches the domestic water heating temperature, the valve 18 will again be opened by the element 23. The cooling of the water supplied through pipe 28 by the heat exchange from inlet pipe 32 is quickly overcome, following stoppage of withdrawal of water from the exchanger, by reason of heat conduction from the boiler water through the pipe 32 to the point of heat exchange relation with the pipe 28.

What is claimed and is desired to be secured by Letters Patent of the United States is:

1. A heating apparatus comprising a hot water boiler having supply and return lines for a hot water radiator, a circulator in the return line to the boiler, a thermostatic valve having a temperature responsive operating element and positioned in the return line to control flow to the circulator, and a by-pass conduit leading from

said boiler to said return line in heat exchange relation with said operating element.

2. A heating apparatus comprising a hot water boiler having supply and return lines for a hot water radiator, a circulator in the return line to the boiler, a thermostatic valve having a temperature responsive operating element and positioned in the return line to control flow to the circulator, a domestic water supply heat exchanger in said boiler and having a cold water inlet line, and a by-pass conduit leading from said boiler to said return line in heat exchange relation with said operating element, said by-pass conduit having heat exchange relation with said inlet line anterior to its exchange relation with said element thereby to influence said element by the temperature of said inlet line.

3. A heating apparatus comprising a hot water boiler having supply and return lines for a hot water radiator, a circulator in the return line to the boiler, a thermostatic valve having a temperature responsive operating element and positioned in the return line to control flow to the circulator, a domestic water supply heat exchanger in said boiler, and a by-pass conduit leading from said boiler adjacent said exchanger and opening into said return line between said circulator and said valve, said conduit conveying boiler water in heat exchange relation with said operating element so that said element will be influenced by the temperature of said exchanger.

4. A heating apparatus comprising a hot water boiler having supply and return lines for a hot water radiator, a circulator in the return line to said boiler, a valve casing in said return line on the inlet side of said circulator, a valve member in said casing and controlling flow to said circulator, said casing having a chamber communicating with said return line on the outlet side of said valve member, a temperature responsive operating element for said valve and positioned in said chamber, and a by-pass pipe leading from said boiler to said chamber for flow of boiler water in heat exchange relation with said element upon operation of said circulator.

5. A heating apparatus comprising a hot water boiler having supply and return lines for a hot water radiator, a circulator in the return line to said boiler, a valve casing in said return line on the inlet side of said circulator, a valve member in said casing and controlling flow to said circulator, said casing having a chamber communicating with said return line on the outlet side of said valve member, a temperature responsive operating element for said valve and positioned in said chamber, a domestic water supply heat exchanger in said boiler and having a cold water inlet line, and a by-pass pipe leading from said boiler adjacent said exchanger to said chamber for flow of boiler water in heat exchange relation with said element upon operation of said circulator, said pipe having intimate heat exchange relation with said inlet line so that said element will be influenced by the temperature of said inlet line.
